VACUUM CLEANER

Klaas Tienens Oord, The Hague, Netherlands, assignor to Verenigde Stofzuigerfabrieken N.V., Leeuwarden,
Netherlands, a corporation of the Netherlands

Filed July 29, 1964, Ser. No. 81,055

Term of patent 14 years

(Cl. D9—2)

FIG. 1 is a perspective view of a vacuum cleaner, showing my new design;

FIG. 2 is a left side elevational view thereof;

FIG. 3 is a right side elevational view thereof;

FIG. 4 is a bottom plan view thereof;

FIG. 5 is a top plan view thereof;

FIG. 6 is a rear elevational view thereof;

FIG. 7 is a front elevational view thereof; and

FIG. 8 is a fragmentary detail view taken from the right side of the vacuum cleaner as shown in FIG. 6.

I claim:

The ornamental design for a vacuum cleaner, as shown.
